Baron D'Urville's Review for stone plates

No 2.

Plate 3

Joseph Nutt's design for stone plates.

No. 3.

No. 4.

Ms. 391

Joseph Pratt; Boston, Mass.

Letters Patent. No. 391. Dated July 8, 1857.

The Schedule referred to in these Letters Patent and making part of the same

To all Persons to whom these Presents shall come:

Be it known that I, Joseph Pratt
of Boston in the County of Suffolk and State of Massachusetts
have produced a new and useful design for the top and
bottom plates of a parlor stove, and I do hereby declare
that the said new design is fully described and rep-
resented in the following specification and accompanying
drawings, to which reference is herein-after made.

The figures of the accompanying plates
of drawings represent my new design. In plate 1, fig. 1
is a plan or top view of the bottom plate. In plate 2,
fig. 2 is a plan of the top plate with the cover. Figs 3 & 4
plate 3 are sections of the bottom and top plates, taken in
the plane of the lines A B and C D respectively.

The bottom plate is of the shape
shown in fig. 1. Nearly all around its edge which is
curved as shown in the section are twined the vines
aa from which spring the flowers and leaves B B - c c &c
Near these and conforming to the shape of the plate, is
the flat raised moulding d d. The moulding around the
elliptical space in which the body of the stove is placed, is
ornamented with the pieces of flower or leaf work e e &c
between each of which is the small scale work f f. Around
this last moulding is the bead moulding g g. Nearly
all around the moulding g g. is the flat moulding
h h, with semi-circular openings enclosing the small
hemispheres i i &c. Between these and the flat moulding
d d, before referred to, are the ribs and grooves k k. &c.
l l &c occupying each corner and one side of the plate.

Around the edge of the top plate are

34
 closely entwined the vines m m &c. from which spring the flowers n, n - o, o. Below and above these are the mouldings h h - q q. The space between this moulding q q and the moulding covered with the ornamental flower and leaf work p p, is occupied with the scales S, S. Above the leaf work p p, are the mouldings a', b', c', d'.

The space between the centre piece, composed of curves t, t &c. on which the cover rests, and the moulding d' is ornamented with the bead work w w. The cover is ornamented with the scale work u u, the leaves x x forming the edge of the same.

Having thus described my new design I shall state my claim as follows.—

What I claim as my production and desire to have secured to me by Letters Patent is, the design consisting of the ornamental configurations, flower and leaf work herein above described and represented in the drawings respectively, for the top and bottom plates of a parlor stove.
